UNITED STATES PATENT OFFICE.

PIETRO DALL'ORTO, OF GENOA, ITALY.

ROTARY ENGINE.

SPECIFICATION forming part of Letters Patent No. 268,719, dated December 5, 1882.

Application filed June 9, 1882. (No model.) Patented in Italy October 14, 1881, No. 197; in France December 8, 1881, No. 134,246; in Belgium December 16, 1881, No. 40,863; in England December 23, 1881, No. 5,641; in Austria December 24, 1881, and in Germany January 3, 1882, No. 13,305.

To all whom it may concern:

Be it known that I, PIETRO DALL'ORTO, a subject of the Kingdom of Italy, residing at Genoa, Italy, have invented certain new and useful Improvements in Rotary Engines, of which the following is specification.

The present invention relates to that class of engines in which a rotary disk provided on its periphery with a piston or projection operates in a steam-chamber containing a movable abutment, the position of the latter in relation to the piston being controlled by a cam, link, and crank mechanism receiving motion from the axis of the piston-disk.

The invention consists in the combination of two rotary disks fitted on the same shaft, and each provided with a peripheral piston or projection located diagonally opposite to each other. These projections operate in independent steam-chambers having curved ports for the ingress of steam, and the disks or projections are provided with passages for admitting steam into a chamber or space formed by said pistons, and oscillating abutments located at the top of the steam or working chambers. The admission of the steam into these chambers takes place so long as the piston-ports are opposite the curved openings in the working-chambers, and the various ports are so located that the steam acts first upon one piston with its full initial force to effect a quarter-revolution of the shaft, then expansively upon the same piston to cause the shaft to make another quarter-revolution, and finally by the action of the steam upon the other piston in a manner the same as with the first piston the shaft is caused to make a complete revolution.

The invention also consists in an oscillating abutment and cam, link, and crank mechanism for operating the same from the shaft of the rotary pistons, as will hereinafter be more fully set forth.

In the accompanying drawings, Figure 1 represents a cross-section of the engine. Fig. 2 represents a longitudinal section through the axis of the cylinder. Fig. 3 represents an end view of the engine. Figs. 4 and 5 are cross-sections representing the interior of the two ends of the cylinder and the cylindrical cap or

lining. Fig. 6 represents the interior and Fig. 50 7 the exterior of the end cover with the orifices for the admission of the motive fluid, and Fig. 8 represents the double cam for operating the rotary stop or abutment.

A is the cylinder, which is divided into two working-chambers by means of a central partition; or two independent cylinders may be secured together, as is shown in Fig. 2. These chambers contain two pistons or, rather, disks fixed upon the shaft E. These disks B are each provided with a tooth or projection, M. These projections are placed opposite to each other, as shown at Fig. 1, in which one of the said projections is shown by dotted lines and the other by full lines. In Fig. 2 the two projections are shown in position diagonally opposite to each other. The cylindrical cap or lining L is placed beneath the projection M of the piston in such manner that an annular space is left in which the projection M turns, such annular space being formed between the sides or ends A' and the cylindrical parts of the cylinder A and the surface of the cap or lining L. In Fig. 1 the piston B is shown in the position it would assume at the moment when it receives the impulse from the steam which enters by the orifice J in the end cover shown at Fig. 4 and by the orifice H in the piston B. The steam exerts its pressure upon the projection M by pressing against the abutment C, 55 and in this way this projection accomplishes a quarter of its course, being pushed by the direct pressure of the steam. Then the opening H in the piston corresponding no longer with the opening J in the cover by which the steam enters, the latter is cutoff, and then acts only by expansion for the remainder of its course. The projections M of the pistons being in position diagonally opposite to each other and the steam acting upon them equally 60 but not at the same time, it results therefore that there is a quarter-revolution given to each with the full pressure of steam—that is to say, the shaft will make a semi-revolution with full steam. The steam may escape by the tube F into the air or into a condenser. The abutments C, turning to the right or to the left, permit the passage of the projections M, after 65 70 75 80 85 90 95

which they serve as abutments for the steam. The reciprocating circular motion of the abutments C is obtained by means of the double cams D, secured to the shaft E and imparting motion to the connecting-rods P, which carry bottom rollers, R, traveling on the cams, and are connected with cranks S on the abutments. The rods P are slotted for the passage of the shaft E. The cams are shown at Figs. 2 and 3 in the position they would occupy when one of the pistons is working by the full pressure of the steam and the other by expansion of the steam, the latter escaping by the tube F.

In Fig. 2, m m represent the stuffing-boxes for the shafts of the abutments C.

If it is desired to reverse the motion of the engine, then by valves (not shown in the drawings) the passages J are closed, and those marked K are opened, by which means the steam is caused to enter the cylinder through passages H' on the opposite side of the projection M of the piston, thereby causing the latter to move in the contrary direction. Simultaneously with the opening and closing of the passages J and K by means of levers the position of the abutments C is changed, in order that they may serve as abutments for the steam in the contrary direction.

The cylinder A is fixed by bolts upon the

base Z, upon which are also fixed the standards N of the shaft E.

Having thus described the nature of the said invention, and the mode in which the same is carried into effect, I would have it understood that what I claim is—

1. In a rotary engine, the combination of the cylinder A, having two independent working-chambers, provided with curved or elongated inlet-ports J and K and outlet-passages F, and shaft E and disks B, having projections or pistons M, located diagonally opposite to each other, and provided with inlet-passages H H', with movable abutments C, and means, substantially as shown, for operating the same, as and for the purpose set forth. 45

2. The combination of the curved oscillating abutments C, cranks S, slotted links P, and rollers R with the shaft E, double cams D, disks B, and pistons M, as and for the purpose set forth. 50

In testimony that I claim the foregoing as my invention I have signed my name, in presence of two witnesses, this 6th day of December, 1881.

PIETRO DALL' ORTO.
